UNITED STATES PATENT OFFICE

107,930

DESIGN FOR A TEXTILE FABRIC

Stanley S. S. McNeil, New York, N. Y.

Application December 1, 1937, Serial No. 73,291

Term of patent 3½ years

To all whom it may concern:

Be it known that I, Stanley S. S. McNeil, a citizen of the Dominion of Canada and residing in the city of New York, county of New York, and State of New York, have invented a new, original, and ornamental Design for a Textile Fabric, of which the following is a specification, reference being had to the accompanying drawing, forming a part thereof, showing an ornamental design for a textile fabric.

I claim:

The ornamental design for a textile fabric substantially as shown.

STANLEY S. S. McNIEL.
